Primary Examiner — Mary Ann Calabrese*Assistant Examiner* — Natalya M Rapundalo(74) *Attorney, Agent, or Firm* — Brooks Kushman P.C.(57) **CLAIM**

The ornamental design for a clip for food storage container, as shown and described.

DESCRIPTION

FIG. 1 is a front elevation view of a clip for food storage container;

FIG. 2 is a right elevation view thereof; and,

FIG. 3 is an upper right perspective view thereof.

The broken lines in the drawings represent a food storage container and form no part of the claimed design.
